VALVE STRUCTURE FOR COMBINED FORMATION TESTING TOOLS AND PRESSURE RECORDERS

Howard D. Kinney, El Dorado, Ark., assignor to
Sterling P. Bedingfield, Bossier City, La.

Application January 29, 1940, Serial No. 316,262

7 Claims. (Cl. 251—78)

This invention relates to testing devices for oil wells, and more particularly to a valve structure for a combined formation testing tool and rock pressure recorder.

The object of the invention is to provide a strong, compact and thoroughly efficient tool of the character described embodying in its structure, means whereby formation tests of oil wells may be quickly made and the true rock pressure of sub-strata accurately recorded so as to insure the use of proper equipment during subsequent drilling operations.

A further object of the invention is to provide means for recording the hydrostatic or rock pressure of the lower strata under relief conditions, that is to say, while permitting the escape of fluid and drilling mud from the rat hole or lower strata into the drill stem, and means for recording the true or actual standing rock pressure of the lower strata when the fluid relief mechanism is cut off.

A further object is to provide a ported sleeve valve member which coacts with spring-pressed closure members for controlling the flow of fluid from the packer to the drill stem whereby a complete shut-off or seal for fluid is effected while the tool is being withdrawn from the well.

A further object is to provide a novel packer unit and means interposed between the packer unit and the adjacent end of the tool casing for preventing the passage of fluid from the large bore to the smaller bore of the well during the process of making a test.

A further object is to provide means for equalizing the hydrostatic pressure between the fluid in the well bore and rat hole thereby to permit easy withdrawal of the tool from the well.

A still further object is to provide the lower portion of the drill stem with a sectional cut-off plug which normally prevents the flow of liquid upwardly into the drill stem, said plug sections being movable to release position either by the impact of a weight introduced within the drill stem or the pressure of fluid forced downwardly through said drill stem.

Further objects and advantages will appear in the accompanying specification and claims forming a part thereof.

In the accompanying drawings forming a part of this specification and in which similar numerals of reference indicate corresponding parts in all the figures of the drawings,

Figure 1 is a vertical sectional view of a combined testing tool and rock pressure recorder embodying the present invention, the packer

being shown ready to seat in the rat hole and the fluid cut-off device in closed position.

Figure 2 is a similar view showing the packer fully seated and the fluid cut-off device and sectional plug in open position.

Figure 3 is an enlarged detail vertical sectional view of the fluid cut-off device and its associated parts.

Figure 4 is a transverse sectional view taken on the line 4—4 of Figure 3.

Figure 5 is a detail vertical sectional view of the recorder showing the manner of mounting the same within the casing.

Figure 6 is a transverse sectional view taken on the line 6—6 of Figure 5.

Figure 7 is a detail transverse sectional view of the connection between the pressure gauge and intake port of the recorder housing.

Figure 8 is a plan view of the chart or graph of the recorder.

The combined formation testing tool and rock pressure recorder forming the subject-matter of the present invention is principally designed for use in oil wells, and by way of illustration is shown in an oil well in which 5 indicates the upper or large bore and 6 the small lower bore or rat hole. The device comprises a casing indicated as a whole at 7, and preferably formed in two sections 8 and 9, one of which is provided at its upper end with a reduced threaded nipple 10 for engagement with the threaded end of the adjacent section whereby said sections are detachably united. Slidably mounted in the upper section 9 is a stem 11 having a vertical bore 12 and provided with an annular stop flange 13 adapted to bear against a stop shoulder 14 formed on the section 9, as shown, there being a screw 15 threaded in the wall of the section 9 with its inner end reduced and fitting in an opening of the flange 13 for preventing rotation of the stem 11 within the section 9. The stem 11 fits within a packing gland 16 and the upper end of the stem is threaded at 17 for engagement with a coupling collar 18 which is, in turn, threaded on the adjacent end of the tubular drill stem, indicated at 19. Threaded within the coupling sleeve 18 is a ring 20 having a stepped lower face 21 adapted to receive a cut-off plug 22. The cut-off plug 22 is preferably of inverted conical shape in cross section and formed in two sections which are fitted together when the cut-off plug is inserted in the ring 20 so as to prevent the passage of fluid from the bore 12 upwardly into the drill stem when making a formation test but are readily separable under the impact of a weight 23 intro-

50
55

duced within the drill stem so as to permit the passage of fluid into said drill stem when it is desired to fill or partially fill the drill stem with liquid for testing purposes, as best shown in Figure 2 of the drawings.

Threaded in the lower end of the stem 11 and movable therewith is a sleeve valve member 24 having a central longitudinal bore 25 which communicates with the bore 12 and is provided near its lower end with a transverse port 26 intersecting the bore 25, as best shown in Figure 3. The side walls of the member 24 are cut away to form parallel guiding ribs 27 between which are mounted closure members, indicated at 28. The closure members 28 are preferably in the form of plates having laterally extending flanges 29 at their upper and lower ends and which receive between them the reduced ends of tubular members 30 mounted within a housing 31, the latter being fitted within the section 9 and resting on the end of the nipple 10 of the section 7. Disposed within the tubular members 30 are coiled springs 32, one end of each of which bears against the housing 31 and the other end thereof against the adjacent closure member 28 and serve to normally and yieldably hold the members 28 in frictional engagement with the sleeve valve member 24 and thus close the port 26.

Surrounding the lower end of the stem 11 and bearing against the housing 31 and lower face of the flange 13, respectively, is a heavy coiled spring 33, the purpose of which is to return the stem 11 to elevated position after said stem, with the drill stem attached thereto, has been lowered to effect the opening of the port 26, as will be more fully explained hereinafter.

The lower section 7 is provided with an interior chamber 34 in the end of which is threaded a reducing plug 35 having a vertical bore 36 of any desired size formed therein and which bore forms a source of communication between the chamber 34 and a chamber 37 in the nipple 10. Threaded in the lower end of the casing section 7 is a closure plug 38 and secured to and depending from said closure plug is a guide tube or stem 39 on which is slidably mounted a packer, indicated at 40. The walls at the upper end of the guide tube 39 are formed with perforations 41, and secured to the lower end of the guide tube 39 by a coupling nipple 42 is a perforated entering head 43. The packer 40 is retained in position on the guide tube 39 by a cap 44, which cap is threaded on a bearing sleeve 45 fitted within the packer so as to move therewith. Bearing against the upper end of the packer 40 and threaded on the bearing sleeve 45 is a metallic plate or washer 46 which coacts with a resilient packing disc 47 preferably formed of rubber or other yieldable material and which, when in engagement with the washer 46, serves to form a liquid-tight joint between the packer and the adjacent end of the casing, as best shown in Figure 2 of the drawings. Inasmuch as the disc 47 is formed of rubber or other yieldable material, any small particles such as sand, grit and the like will be embedded in the disc 47 and thus allow said disc to firmly contact with the plate or washer 46 so that the liquid cannot escape between the parts.

As a means for recording the hydrostatic or rock pressure of the lower strata of the well bore, there is provided a recording mechanism of the type shown in Figure 5 of the drawings. The recording mechanism comprises a casing 48 consisting of upper and lower sections provided with

registering lugs 49 and defining intermediate fluid passages 50, the lugs being formed with perforations for the reception of bolts or similar fastening devices 51, whereby the sections of the casing may be firmly secured together. The lower section of the recorder casing 48 is provided with a depending nipple 52 and formed in said lower casing section and communicating with the nipple 52 and with the interior of said casing section is a passage or bore 53. Disposed within the lower section of the casing 48 is a pressure gauge 54 of any suitable construction but preferably in the form of a curved pipe or tube, one end of which communicates with the passage 53, as indicated at 55. Disposed adjacent the end 55 of the gauge is a support 56 on which is pivotally mounted, at 57, one end of a lever 58 carrying a pencil, scribe or other suitable marker 59 adapted to record the pressure on a revolving dial or graph 60. The lever 58 is connected to the gauge 54 by means of a link 61 so that expansion and contraction of the gauge will effect a corresponding movement of the marker 59 over the surface of the dial or graph 60. Disposed above the dial 60 is a timing device 62 preferably in the form of a clock and the graph or dial 60 is connected to the central arbor 63 of the clock so as to be rotated thereby. The dial or graph 60 is provided with suitable graduations and is adapted to make one revolution each hour so that not only will the rock or hydrostatic pressure be recorded on the dial 60 but also the exact time at which the test or tests were made. Inasmuch as the casing of the recorder is made in two sections, said sections may be readily detached so as to obtain access to the interior of the mechanism and permit the removal of the graph or dial after the tests have been made.

In operation, the tool is attached to the lower end of the drill stem and lowered into the large portion of the well bore until the packer 40 rests on the ledge at the upper end of the rat hole 6. The packer now remains stationary and the remainder of the tool, by a continued lowering, forces the tubular guide or stem 39 through the packer until the packing disc 47 rests upon the washer 46 of said packer, thereby stopping further downward movement of the casing 9. The drill stem 19, carrying with it the stem 11 and its associated parts, continues its downward movement, however, thereby compressing the spring 33 and forcing the ported sleeve valve member 24 downwardly between the closure members 28. This downward movement of the sleeve valve 24 causes the port 26 to extend below the extremities of the closure members 28 for the purpose of allowing fluid to enter into the upper portion of the tool and as the sectional plug 22 is closed, the fluid cannot enter the drill stem 19. With the parts in this position, fluid passes upwardly through the guide tube or stem 39, nipple 52 and port 33 into the housing of the recording mechanism where it acts upon the pressure gauge 54 and actuates the latter to move the pencil or scribing device 59 over the surface of the dial or graph 60 to record thereon the rock or hydrostatic pressure. This recording of the pressure is effected under relief conditions, that is to say, while permitting the escape of fluid and drilling mud from the rat hole or lower strata through the bore of the relief plug 35. The parts are allowed to remain in this position for a predetermined length of time, after which the weight or impact member 23 is permitted to fall on the plug 22, 75 the impact of the weight causing the plug sec-

tions to drop to the position shown in Figure 2 of the drawings and in which position fluid is permitted to enter the drill stem. The parts are allowed to remain in this position for a short time which causes the recording mechanism to indicate the true hydrostatic or standing rock pressure and also the time the test was made. The tool is then withdrawn from the well and the recording mechanism removed from the section 8 through the end of said section after the plug 38 has been removed. The clamping bolts 51 of the recorder casing are then detached and the casing sections removed, thus exposing the dial or graph 68 and permitting the operator to read the indications thereon and thereby be in a position to use proper equipment during subsequent drilling operations. As the tool is withdrawn from the well, the guide tube or stem 39 will slide upwardly through the packer until the coupling 42 engages the cap 44 when the packer will be carried upwardly with the tube. During withdrawal of the tool from the well, expansion of the spring 33 will force the stem 11 upwardly until the flange 13 contacts with the shoulder 14 and in which position the port in the member 24 will be automatically cut off by the closure members 28. The difference in the hydrostatic or rock pressure between the well bore and the rat hole is equalized by permitting the passage of fluid through the ports 41 or perforations 43, thereby permitting the ready withdrawal of the tool. It will here be noted that when the resilient disc 47 contacts with the washer 46, any particles of sand or other foreign matter will be embedded in the resilient material of which the disc is formed so as to insure a tight fluid seal between the lower end of the section 8 and the packer.

It often occurs while removing tools of various kinds from the well bore that it is necessary to pump fluid down through the tubular drill stem into the well bore for the purpose of agitating fluid, mud and the like and when this becomes necessary, fluid pumped into the drill stem under pressure will force the cone sections of the plug downwardly to open position so that the fluid can pass through the bore 12 into the port 25 forcing the closure members away from the surfaces of the member 24 and thus allowing the fluid to pass down and out through the openings 41 or perforations 43 into the well bore.

Owing to the formation of the valves or closure members 28 and their frictional contact with the sleeve valve member 24, said closure members will have a tendency to shear or cut any foreign objects such as sticks, rubber, or the like which would tend to interfere with the proper operation of the ported sleeve valve. Furthermore, as the closure members and sleeve valve are always and at all points of travel in direct and close contact, sand, grit and the like are effectively prevented from getting between the smooth contacting surfaces.

The present invention not only provides a means for obtaining the rock or hydrostatic pressure prior to completion of a well, but also accurately records the pressure under both relief and true conditions, as well as the exact time the test or tests were made. This true pressure reading makes it possible to compute the initial production or barrelage of an oil well prior to completion of the well. The data thus obtained may be preserved for future use and will be found of extreme value from a geophysical and geological standpoint.

While I have shown and described a preferred form of recording mechanism in association with the testing tool, it will, of course, be understood that any other type of standard recording mechanism may be used in lieu thereof, the essential feature of the invention, in addition to its novel construction and operation, residing in the employment of a recording mechanism in combination with a formation testing tool whereby the results of the tests may be recorded and a permanent record kept thereof.

From the foregoing description, it is thought that the construction and operation of the device will be readily understood by those skilled in the art and further description thereof is deemed unnecessary.

Having thus described the invention, what is claimed as new is:

1. A valve structure for well testing tools comprising a casing, a hollow stem slidably mounted within the casing, a sleeve valve member secured to the sliding stem and provided with spaced longitudinal guide ribs and a transverse port disposed between the guide ribs, spring actuated closure members engaging the sleeve valve member between the guide ribs, and a spring surrounding the stem for moving the sleeve valve member to closed position.

2. A valve structure for well testing tools comprising a casing, a hollow flanged stem slidably mounted within the casing, a ported sleeve valve member carried by and movable with the flanged stem, a housing arranged within the casing, closure members coacting with the port of the sleeve valve member and provided with upper and lower lateral flanges, tubular members disposed within the housing between said flanges, springs fitting within the tubular members and bearing against the closure members, and a spring surrounding the stem and having one end thereof bearing against the housing and its other end engaging the flange on said stem.

3. A valve structure for well testing tools comprising a casing, a hollow flanged stem slidably mounted within the casing, a ported sleeve valve member carried by and movable with the flanged stem, spring pressed closure members coacting with the port of the sleeve valve member, and a spring interposed between the closure members and the flange of said sliding stem.

4. A valve structure for well testing tools comprising a casing, a hollow flanged stem slidably mounted within the casing, a sleeve valve member carried by the flanged stem and provided with a transverse port, spring actuated closure members for controlling the passage of fluid through said port, and yieldable means interposed between the closure members and the flanged stem for normally holding the port in the sleeve valve member covered by said closure members.

5. A valve structure for well testing tools comprising a casing, a hollow stem slidably mounted within the casing, a sleeve valve member secured to the sliding stem and provided with spaced longitudinal guide ribs and a transverse port disposed between the guide ribs, and spring actuated closure members engaging the sliding valve member between the guide ribs.

6. Valve structure for well testing tools comprising a sectional casing, one section of which is provided with a stop shoulder, a hollow stem slidably mounted within the shouldered section and provided with a flange adapted to bear against said shoulder, said sliding stem being

formed with a longitudinal bore, a sleeve valve member secured to the lower portion of the sliding stem and provided with a longitudinal bore communicating with the bore of the stem, a transverse port intersecting the bore of the sleeve valve member, a housing disposed within the shouldered section, closure members arranged within the housing and coacting with the sleeve valve member to close the port therein, and springs for yieldably holding the closure members against the sliding valve member.

7. A valve structure for well testing tools comprising a casing formed of upper and lower sections, one of which is provided with a threaded

nipple for detachable engagement with the mating section, a stem slidably mounted in the upper section and provided with a longitudinal bore, a sleeve valve member carried by and movable with the sliding stem and provided with a transverse port, a housing disposed within the upper section and resting on the nipple, tubular members arranged within the housing, flanged plates fitting over the tubular members and constituting closure members for controlling the passage of fluid into the transverse port, and springs disposed within the tubular members and bearing against said flanged plates.

HOWARD D. KINNEY.
